WRAPPING MACHINE

Leon V. Whipple and James D. Wells, Floral Park,
N. Y., assignors to American Machine and
Foundry Company, a corporation of New Jersey

Application May 19, 1942, Serial No. 443,584

29 Claims. (Cl. 93—2)

This invention relates to wrapping machines suitable for wrapping any kind of package, object or article, such as bread, boxes, etc., and consists chiefly in improvements in the mechanism for handling the wrapper at various stages of the web feeding and wrapping operations, and to mechanism for draping or positioning the wrapper in the path of an article or object to be wrapped.

The subject matter of this invention relates to wrapping machines in general and more specifically to wrapping machines of the type shown in Schmitt Patent No. 1,851,295, granted March 29, 1932, in which articles being wrapped are moved against a draped wrapper onto a lifter table, raised, and transported through the machine past suitable folding and sealing mechanisms to complete each package, although the mechanism shown and described is readily adaptable for use with other types of wrapping machines.

In wrapping machines of this type, and in bread wrapping machines in particular there is often some difficulty in properly associating the wrapper with the loaf so that the least amount of wrapper will be used per loaf and the wrapper will be disposed properly relative thereto before the loaf to be wrapped engages the wrapper and moves therewith onto the lifter table. This is due in part to the fact that each loaf may vary somewhat in dimensions, and when a machine is being run at high speed it is quite possible that more difficulty will be experienced if the wrapper is not properly fed or disposed with respect to the loaf to be wrapped.

In wrapping machines of the type under discussion in which a lap roller is utilized to pull the wrapper and drape it in the path of an oncoming loaf, it so happens that at high speeds there may be an uneven pull on the wrappers. That is, the rapidly moving lap roller when moving into engagement with the paper and exerting a downward pull thereon may cause the paper to shift laterally with the net result that the web is not properly disposed with respect to the loaf or article being wrapped and hence imperfect packages are formed.

It also happens in a machine employing an oscillating lap roller, that this type of lap roller, which moves back rapidly to inoperative position following its cycle of operations, may strike one edge of the paper before the other thereby causing an imperfect feed of the web, and also the cut end of the draped wrapper may fly upward due to the engagement therewith of the rapidly moving lap roller as it moves back to its inoperative position above the infeed runway over which the next article to be wrapped is moving.

According to our invention we have provided a novel lap roller mechanism in which one or more lap rollers are mounted on endless traveling members, such as chains, and are operated in timed relation with the movement of the lifter table of the wrapping machine in such a way that during each cycle of the machine one lap roller moves into engagement with the wrapper and travels therewith in a closed unidirectional path to dispose the wrapper properly with respect to the next article to be wrapped. Our mechanism is rugged in construction, is simple to adjust, and thereby makes it possible to always feed the correct length of wrapper web. At the same time the lap roller or rollers are mounted for a constant length stroke thereby permitting easy adjustment of the stroke by mechanism positioned outside the machine.

Accordingly it is an object of our invention to provide improved wrapping mechanism wherein novel means are provided for feeding and disposing the paper in the path of an article to be wrapped.

Our invention also consists in the provision of a novel lap roller paper handling mechanism for use in a wrapping machine in which each lap roller or rollers, as the case may be, moves through an endless path in a single direction in order to engage the paper simultaneously across its width, and travel therewith to dispose the web in the path of an article to be wrapped and which roller or rollers because of its construction continues its movement away from the paper after the web has been cut, and thereby eliminates any danger of flying paper which might cause an interruption in the operation of the wrapping machine or the formation of imperfect packages.

It is a further object of our invention to provide a wrapping machine utilizing a plurality of lap rollers mounted on endless traveling members and to control the movement of the traveling members such that during each cycle of the machine a single roller is responsible for the proper feed and disposition of a wrapper in the path of an article to be wrapped.

It is a further object of our invention to provide a wrapping machine employing an improved paper handling mechanism which eliminates the danger of breakage of parts and greatly lessens the danger of flying paper which has been present in existing machines of this type.

It is a further object of our invention to provide improved lap roller mechanism for a wrapping machine which employs endless chains provided with a plurality of equally spaced lap rollers, each roller being operative during recurring cycles of the machine to dispose the

wrapper web properly with respect to articles to be wrapped.

Our invention also consists in the provision of novel lap roller operating mechanism in which each lap roller has a constant length stroke and wherein means are provided for effecting easy adjustment of the stroke position of the several rollers.

Our invention also consists in the provision of novel wrapper handling mechanism for a wrapping machine including simplified adjusting mechanism whereby with considerable simplicity an operator will be able to control the correct length of the inner lap of the wrapper on each package.

Our mechanism also permits elimination of plates or gap closers which heretofore have been considered as essential for proper introduction of articles, such as loaves of bread, onto the lifter table while at the same time we maintain an acceptable lap roller path.

With these and other objects not specifically mentioned in view, the invention consists in certain combinations and constructions which will be hereinafter fully described, and then set forth in the claims hereunto appended.

In the accompanying drawings which form a part of this specification, and in which like characters of reference indicate the same or like parts:

Figure 1 is a partial side elevation of the improved wrapping machine;

Figure 2 is a plan view of the same taken on line 2—2 of Figure 1;

Figure 3 is an enlarged sectional view of the lap roller chain adjusting mechanism;

Figure 3a is a sectional view of Figure 3 taken on line 3a—3a;

Figure 4 is a view taken on line 4—4 of Figure 2;

Figure 5 is a view taken on line 5—5 of Figure 2 showing certain details of the lap roller mechanism;

Figure 6 is a plan view taken on line 6—6 of Figure 5;

Figure 7 is a partial front elevational view of a detail showing the general arrangement of the cutting mechanism and lap roller unit; and

Figures 8 to 11, inclusive, are detail views illustrating diagrammatically the position of the package and wrapping material during various stages of a wrapping cycle.

Referring to the drawings which show a preferred embodiment of our invention, the side frames 2 of the wrapping machine support a drive shaft 4 mounting a gear 6 meshing with a gear 8 on cam shaft 10 which supports a cam 14 provided on opposite sides with cam tracks 16 and 18. Mounted on fulcrum shaft 12 is a lever 22 provided with cam follower 20 operating in track 16 of cam 14, and pivotally joined to lever 22 is an adjustable connecting rod 24 pivotally connected to lifter table 26 swingably mounted on shaft 28 supported in side frames 2. A lever 32 fulcrumed on shaft 12 is provided with a cam follower 30 traveling in track 18 of cam 14 and adjustably connected to lever 32 is a connecting rod 34 which is joined at its other end to lever 36 fulcrumed on a cross shaft 38 supported by side frames 2, and provided with an arm 40 connected by a link 42 to reciprocating plunger 43 guided in members 44 of a bracket 45 carried by cross rods 46 of the machine. Plunger 43 at its inner end is provided with a pusher plate 47 adapted to engage each article to be wrapped as it is fed into the machine by suitable mechanism

(not shown), propel the same across the inclined runway 48 and thereby deliver each article with a wrapper W' onto lifter table 26 when the lifter table is in its lowermost position, as indicated in dotted lines in Figure 1. The plates 48 are suitably mounted upon the side frames 2 of the machine, and are so positioned with respect to the lifter table that additional article supporting means are unnecessary in order to properly guide articles to be wrapped onto the lifter table. As an article is moved by pusher 47 onto lifter table 26, it engages a back article supporting device 50 having a back supporting plate 51 carried by the lifter table 26. This back supporting plate may be of the same general construction as that described in co-pending application, Serial No. 418,880 filed November 13, 1941, by J. Stein and L. Whipple for Bread wrapping machine, but since it forms no part of the present invention, further showing and description thereof is deemed unnecessary. It is to be noted, however, that the back article supporting device 50 is operated in proper timed relationship to position it in article engaging position on the lifter table in order to assist in the wrapping of each article being moved thereon, and to otherwise perform its designated functions. Also mounted on lifter table 26 is a rod 52 which supports a top tension plate 54 adjustably mounted by any suitable means, such as a set screw 55 on rod 52. The position of plate 54 is adjusted according to the height of articles being wrapped.

After the article with its wrapper (as shown in Figure 1) has been moved onto lifter table 26, the latter is swung about its fulcrum 28 into the full line position of Figure 1 and the wrapper is handled and cut by means to be described hereinafter.

With the lifter table in its "up" position, the wrapper W is partly folded around the package P, with an end hanging down from the rear side of the partially wrapped article, as best seen in Figures 1, 9 and 10. The article is now acted upon by suitable transfer fingers 112 provided with pushers 113 carried by endless traveling members such as sprocket chains 114 running over driven sprocket 115 and idler sprockets (not shown). The pushers 113 engage the back supporting plate 51 and advance it to the front edge of the table. As table 26 starts downward, pushers 113 continue forward passing above the back supporting plate 51 and engage the article advancing said article off the table. As the partially wrapped package is advanced a slight distance along the table 26, a cam actuated knife 162 moves towards a ledger plate 163 carried by the table 26, coacts therewith, and severs the wrapper W'. The continued movement of the pusher 113 advances the article from the table and a cam actuated clamp bar 172 aids in keeping the bottom lap of the wrapper about the article. The mechanism for operating knife 162 and bar 172 may be similar to that shown in the above referred to Schmitt patent.

A reference to Figures 8 to 11, inclusive, will show that the inner lap is formed on the underside of the package as it is moved by pusher 47 onto lifter table 26, and that the outer lap is completed about the article as it is moved by a pusher 113 onto support plate 142 of the foldway. The timing of the machine is such that shortly before the partially wrapped article leaves the lifter table 26, the latter begins to descend and thereby permits pusher 113 to clear the back of

the downwardly moving back supporting plate 51.

Sprockets 115 are so mounted on shaft 130 that they can be adjusted thereon and transfer fingers 112 can be moved relative to a partially wrapped article on the table 26 and through the foldway over supporting surface 142, so that regardless of its width, the fingers do not move the partially wrapped article from the table until it dwells in its upper position (Figure 1). This is accomplished by means of a spacer 128 secured on sprocket shaft 130 and equipped with a bolt 127 passing through an elongated slot 129 in gear 131. It will be seen that when bolt 127 is loosened, the shaft 130 and its attached members can be turned to adjust the fingers 112 to engage the articles being wrapped earlier or later as required.

Gear 131 is driven by a gear 132 mounted on a shaft 133 carried by a suitable bracket (not shown) attached to one of the side frames 2. Shaft 133 also carries an arm 135 provided with an elongated slot 136 adapted to engage a roller 137 carried by an arm 138 fastened on a shaft 139 supported by a suitable bracket (not shown) on the side frames 2, in a manner similar to that shown in the above referred to Stein and Whipple application. Shaft 139 also carries a sprocket 142 engaging a chain 143 running over a sprocket 144 which is mounted on the cam shaft 10, as shown in Figure 1. The motion imparted to arm 135 and its coacting members is such that as the fingers 112 engage the package, the conveyor 114 moves rapidly thus advancing articles being wrapped from the table, but as the fingers continue to advance, the speed of the conveyor gradually decreases thus moving the articles more slowly through the folding zone of the machine (not shown) and over the support 142 to insure proper wrapping and sealing of each package. While only a single chain 114 and sprocket 115 have been shown, it is to be understood that there are two such chains and sprockets, one being mounted adjacent each of the side frames 2, both of which chains are driven by means of sprockets 115.

Referring to Figures 1, and 8 to 11, inclusive, it will be seen that mounted beneath the supporting table 142 of the article foldway is a lap roller mechanism employed for feeding and disposing the wrapper properly with respect to each article moving into the machine in order that a wrapper may be positioned for engagement by each article moving into the machine. The lap roller mechanism employs two lap rollers, although more could be used if desired, mounted for movement in a single direction in a closed path to and from wrapper handling position. According to the preferred form of our invention, side frames 2 are provided with abutments 182 located a short distance beneath the plate 142. These abutments support shaft 186 secured by pins 183 in abutments 182 extending inwardly from the frame and having secured thereto arms 184 in the ends of which are screwed or otherwise suitably affixed stud shaft 186 mounting sprockets 188 tracked by chains 190 running on sprockets 192 mounted on shaft 186.

The wrapping web may be fed by any suitable means and located properly for operation thereon by the lap rollers and articles being moved by pusher 47 across infeed guideways 48 against a wrapper and upon lifter table 26. It is evident that in this type of wrapping machine the wrapper is draped from rollers 160 between which

5 wrapper webs are fed from supply reels R, R', downwardly across the discharge end of infeed guideway 48 so that as an article is advanced by pusher 47 it will strike against the draped wrapper W' and move therewith onto lifter table. The web feeding device may be similar to that shown in Schmitt Patent No. 1,841,295 and may feed one or more webs from supply rollers R, R' (Figure 1). The web feeding mechanism is driven from sprocket 158 on shaft 10 by means of a chain 157 tracking sprocket 156 on shaft 155 suitably mounted between the frames 2 of the machine. A belt 153 travels over pulleys 154 on shaft 155 and roller 152 over which roller web R is trained. Webs R and R' then are guided over roller 148 which mounts a pulley 149 driven by means of a crossed belt 161 running on a pulley 146 on roller 152. A gravity roller 163 movable in a slot 165 formed in side frames 2 rides in the loop of paper formed by slack in webs W, W' and assists in maintaining the proper paper balance as the web material fed from reels R, R' is pulled over table 159 past rollers 160 by the lap roller mechanism much in the manner described in said Schmitt application.

One end of shaft 194 is journaled in an elongated block or support 196 fixed to frames 2 by means of bolts 198 and suitable spacing collars 200 (Figure 6). The other end of shaft 194 is 20 mounted in a block 197 suitably secured to the opposite frame 2.

Chains 190 preferably support two or more lap rollers 191 described hereinafter more in detail. If desired, however, a single lap roller might 25 be used.

The lap roller mechanism, just described, is driven in proper timed relationship with the infeed pusher 47, lifter table 26 and other synchronized parts of the machine by means of a 30 cam 202 provided with a track 204 in which travels a cam follower 206 mounted on an arm of lever 208 fulcrumed on shaft 12 and provided with an arm 210 to which is pivotally connected a rack 212. A plurality of holes 213 may be 35 formed in arm 210 in order to adjust the amount of travel of chains 190 if such is desirable.

Rack 212 is guided by a flanged roller 214 rotatably mounted on a stud 216 supported in block 196, and provided with a head 218 having a bore 219 for purposes described hereinafter. Stud 216 is fixed in proper position in block 196 by means of a set screw 220 and in this manner the position of bore 219 is adjusted with respect to a push-out rod 221, to be described hereinafter.

55 Rack 212 meshes with a gear 222 mounted on stud 224 fixed in block 196 (Figure 6). Gear 222 is provided with a hub 226 which may be a separate member, or as shown in the drawings formed integrally therewith. Hub 226 is provided with a cut-out portion or recess 228 with which 60 engages and disengages a tooth 230 on a pawl 232 pivotally mounted at 234 on gear 236 loosely mounted on stud 224, and normally urged into engagement with recess 228 by means of spring 238 fixed at one end to a pin 240 on pawl 232 and at its other end to a pin 242 fixed to gear 236. Gear 236 meshes with gear 244 loosely mounted on shaft 194. In the form illustrated gear 244 is provided with a sleeve extens'on 245 (see Figures 3, 3a and 6) supported in bearing 246 in block 196 and extending through frames 2 (Figure 3).

From time to time it may be necessary for some reason, such as differences in size or shape of articles or loaves of bread going through the

machine, to adjust the position of the lap rollers 191 relative to the lifter table 26 and knife 162, and change the position of the lap rollers so as to retard or advance them for proper operation in the machine cycle. For this reason mechanism has been provided for disconnecting the driving relationship between gear 244 and sprocket 192 in order that sprocket 192 may be turned independently of gear 244 to effect the adjustment of the lap rollers 191a, 191b.

Referring to Figures 3 and 3a which show in detail the make-up of the lap roller adjusting mechanism, it will be seen that in the preferred embodiment, fixed to the end of shaft 194 by means of a set screw, is an adjusting member designated generally 248, having a knurled hand turning wheel 250 and a lock clamp portion 252 adapted to engage sleeve 245. The arms of clamp portion 252 are provided with a set screw 254 for securing gear 244 and sprocket 192 in any desired adjusted position. When, therefore, it is desired to advance or retard chains 190 and lap rollers 191, screw 254 is loosened thereby releasing gear 244 from driving relationship with sprocket 192 and the proper adjustment can be made. While the above described chain and lap roller adjustment can be made at any time, it is preferred to make it when tooth 230 engages recess 228 at which time gears 236 and 244 are held against rotation.

An idler sprocket 256 is provided for each chain 190. These sprockets are mounted on studs 258 supported by adjustable brackets 260, 261. Bracket 260 is provided with an elongated slot 263 and is secured in adjusted position to block 196 by means of screw 262. Bracket 261 is also provided with an elongated slot 263 and is mounted in a similar manner on a block 197 fixed to frame 2 (Figure 2).

Pawl 232 is moved out of engagement with recess 228 during the operation of the machine in order to stop the movement of chains 190 and lap rollers 191 carried thereby. A reference to Figures 5 and 6 shows that knock-out rod 221, which slides in bore 219, is adjustably mounted on a yoke 270 riding on shaft 10 normally held in proper position thereon by means of a spring 223 encircling rod 221 and bearing against head 218 and a plate 271 secured to yoke 270. A cam follower 272 mounted on a stud 274 in yoke 270 tracks a cam 277 fixed to a hub 278 on shaft 10 by means of screw 280. On the other side of the yoke 270, stud 274 carries a follower 282 which is guided in a track 284 of stationary cam 286 fastened by screws 288 to hub 290 of side frame 2.

Figures 8, 9, 10 and 11 illustrate diagrammatically the various phases of operation of the lap roller mechanism and the other parts of the machine which cooperate therewith in the envelopment of articles in wrappers. In Figure 8 an article has been pushed by pusher 47 against a draped wrapper 'W' onto lifter table 26. The upper lap roller 191a dwells beneath knife 162 and as the lifter table moves to the position shown in Figure 9, the remainder of the wrapper web, which is to form the wrapper for the specific article being handled, is pulled down over the fourth side of the article and clamped between clamps, such as rollers 172, 176. Following this operation, rack 212 is moved downwardly (Figure 4) and because of the engagement of tooth 230 on pawl 232 with recess 228 of hub 226, the coaction between gears 236 and 244 is such that sprocket chains 190 are moved and the lap roller 191a (Figure 8) moves into engagement with the

wrapper web extending downwardly from the clamps 172, 176 and between rollers 166 and pulls the free end of the web which has been fed from supply reels R, R' downwardly between rollers 160 to the position shown in Figure 10 whereupon knife 162 is swung inwardly against ledger plate 163 to sever the wrapper 'W' which then drops down and is positioned (as shown in Figure 11) by the downward motion of lap roller 191a, draped and ready to receive the next article to be wrapped. As the lap roller 191a is moving downwardly beneath the lifter table 26 and towards infeed guide plate 48 (as shown in Figure 10), the second lap roller, designated 191b, is moving upwardly to assume the position just vacated by lap roller 191a, and (as shown in Figure 11) at the end of the operating cycle, lap roller 191b has assumed the position formerly occupied by lap roller 191a or the position of lap roller 191a in Figure 8. When the roller 191a reaches the position shown in Figure 11, the high portion 277 of cam 276 engages cam follower 272 which causes yoke 270 to move knock-out rod 221 forward into engagement with the tail of pawl 232, tooth 230 is forced out of recess 228 and movement of chains 190 is stopped.

The invention above described may be varied in construction within the scope of the claims, for the particular device selected to illustrate the invention is but one of many possible concrete embodiments of the same. It is not, therefore, to be restricted to the precise details of the structure shown and described.

What is claimed is:

1. In a wrapping machine having mechanism for wrapping an article in the free end of a web of wrapping material, a member mounted for travel across the path of a succeeding article to be wrapped while said first-named article is partially wrapped within the free end of said wrapper, means supporting said member for movement in a closed unidirectional path, means for advancing said article to complete the circumferential wrapping of said article in said wrapper, and means for moving said supporting means to travel said member in a closed unidirectional path to pull a loop-length of said web for forming the next wrapper.
2. In a wrapping machine having mechanism for feeding a succession of articles to be wrapped into said machine, and mechanism for wrapping an article in the free end of a web of wrapping material draped in the path of articles introduced into said machine, means for advancing the partially enwrapped article to complete the circumferential wrapping of said wrapper thereabout with a portion of said web projecting outwardly away from said article, a traveling member arranged to engage said projecting portion of said web, spaced conveyor elements supporting said member for movement in a closed unidirectional path, and means for driving said elements to move said member in a closed unidirectional path and in a single direction to pull a portion of said web and drape said pulled portion web in the path of the next article of the succession to be wrapped.
3. In a wrapping machine, means for supporting a portion of a web of wrapping material in the path of an article to be wrapped, a web displacing member, spaced conveying means mounting said member transversely of said web for movement into engagement with said web and across the path of articles to be wrapped, means for moving said article into engagement with said portion of said web to partially enwrap said

article, means for holding another portion of said web against endwise movement, and means operative after said partial wrapping of said article for moving said conveying means to travel said member in a closed unidirectional path to engage said web and dispose another portion of said web in the path of the next article to be wrapped.

4. In a wrapping machine, means for supporting a portion of a continuous web of wrapping material in the path of an article to be wrapped, a web displacing member, conveying means mounting said member transversely of said web for engagement therewith, means for associating said article with said portion of said web, and means operative after said portion of said web has been associated with said article for moving said conveying means to travel said member in a closed path to engage another portion of said web and dispose said portion of said web in the unidirectional path of the next article to be wrapped.

5. In a wrapping machine having spaced side frames, an infeed guide, a wrapping guide and an article transfer moving between said guides for transferring articles from said infeed guide to said wrapping guide, wrapper handling mechanism mounted between said guides for draping a portion of a wrapper web in the path of articles to be wrapped, said mechanism including endless chains mounted adjacent said side frames, transverse wrapper engaging rods extending across said machine and fastened to said chains, means for moving an article from said infeed guide against a draped wrapper and onto said transfer to partially wrap said article, means for moving said transfer to deliver said partially wrapped article to said wrapping guideway, and means for moving said chains to cause one of said rods to form a loop in said web, means for cutting said web adjacent one end of said loop whereby to dispose another portion of said web in the path of the next article to be wrapped.

6. In a wrapping machine having spaced side frames, an infeed guide located at one level, and a wrapping guide located at another level positioned between said frames, an article transfer moving between said guides for transferring articles from said infeed guide to said wrapping guide, wrapper displacing mechanism mounted between said guides, said mechanism including endless conveyors adjacent said side frames, wrapper engaging members carried by said conveyors and spaced therealong, means for moving an article from said infeed guide onto said transfer and against a positioned wrapper for delivery to said wrapper guide, means for holding said web extended between said articles and members, and means for moving said conveyors to cause one of said members to engage said extended web and to travel from a position adjacent said wrapping guide to a position below said infeed guide and thereby displace a portion of said web relative to said partially wrapped article and dispose the same in the path of the next article to be wrapped.

7. In a wrapping machine having an infeed guide located at one level, a wrapping guide located at another level, and wrapper web support means, an article transfer moving between said guides for transferring articles from said infeed guide to said wrapping guide, wrapper displacing mechanism extending between said guides, said mechanism including endless conveyors, wrapper engaging and feeding members carried by said conveyors and spaced equidistantly therealong, means for moving an article from said infeed guide onto said transfer and against a positioned

5 wrapper for delivery in partially wrapped condition to said wrapping guide, means for supporting another portion of said web between said partially wrapped article and said wrapper web support means, and means for moving said conveyors to cause one of said members to engage said supported portion of said web and travel from a position adjacent said wrapping guide to a position adjacent said infeed guide and thereby dispose an additional portion of said web in the path of the next article to be wrapped.

8. In a wrapping machine having spaced upper and lower article handling guideways, means for draping the free end portion of a continuous wrapper web between said guideways, and a conveyor for projecting an article to be wrapped along said lower guideway into said free end of said continuous web to partially enwrap said article, a device for holding a portion of said web against endwise movement, web feeding and draping mechanism mounted between said guideways, said mechanism including endless conveyors, a plurality of transverse rods secured to said conveyors, and means operative when a partially wrapped article has been positioned adjacent said upper guideway for driving said conveyors to cause one of said rods to engage said web adjacent said device and while said web is held thereby to feed a length of said web and dispose the same in the path of the next article to be wrapped.

9. In a wrapping machine having spaced upper and lower article handling guideways, means for supporting the free end portion of a continuous wrapper web between said guideways, and a conveyor for projecting an article to be wrapped from said lower guideway into the free end of said continuous web; web feeding and draping mechanism mounted between said guideways, said mechanism including endless traveling supporting members, a plurality of transversely extending loop pulling rods secured equidistantly apart on said supporting members, and means for moving said supporting members stepwise in timed relation to articles being advanced by said conveyor and along said upper guideway to advance one of said rods cyclically into engagement with said wrapper web and dispose said web in loop form adjacent the path of the next article to be wrapped.

10. A wrapping machine comprising an article lifter, means for moving said lifter, means to position the free end of a wrapper adjacent said lifter and fold it about an article moved onto said lifter with the web extending uncut therefrom, and mechanism for feeding and disposing a wrapper in the path of an article to be wrapped comprising, traveling members, a plurality of web pulling rods secured to said members, and means for moving said members in timed relation with the movement of said article lifter to drive said members and cause one of said rods to engage said uncut web and pull a loop of web of a length sufficient to form the next wrapper.

11. In a wrapping machine having an article lifter, and means for moving said lifter between an article receiving station, where an article is associated with a wrapper, and an article delivery station, where a partially wrapped article is removed from said lifter, means operative adjacent said receiving station for holding a portion of said web, mechanism for feeding and disposing the free end of a continuous web in the path of an article at said receiving station comprising, traveling members extending between said stations, web engaging and feeding rods supported by said

members and spaced therealong, means normally maintaining one of said rods positioned adjacent said delivery station for engagement with said supported web, while another of said rods is located remote from said delivery station, and means operative after said lifter has located a partially wrapped article at said delivery station for moving said members and said rods, said means being constructed and arranged to travel said first-named rod into engagement with said supported portion of said web to feed a length thereof into the path of the next article fed to said receiving position for wrapping and advance said second named rod to the position vacated by said first-named rod adjacent said delivery station for feeding the next length of web. 15

12. Wrapper feeding mechanism for a wrapping machine comprising, means for suspending a portion of a web between two supports, and mechanism for pulling said web relative to said supports to feed a length of web sufficient to form a wrapper, and to dispose said wrapper in the path of an article to be wrapped, said mechanism comprising conveyors, a device spaced from said means for holding a portion of said web, a plurality of web feeding means secured to said conveyors, and means for intermittently driving said conveyors to travel said web feeding means seriatim between said first-named means and device into feeding and displacing relation with said web. 20

13. Wrapper feeding mechanism for a wrapping machine comprising, means for suspending a portion of a continuous web between two supports, and mechanism for pulling said web relative to said supports to feed a loop length of web sufficient to form a wrapper, and to dispose said wrapper in the path of an article to be wrapped, said mechanism comprising conveyors, a plurality of equidistantly spaced web feeding devices mounted on said conveyors, and means for intermittently driving said conveyors to travel said web feeding devices seriatim into feeding and displacing relation with said web. 30

14. In a wrapping machine having vertically spaced article supporting and guiding surfaces, a lifter table for conveying an article partially enveloped in a wrapper from one surface to the other, a web feeding guide, and means associated with said lifter table for clamping a portion of said wrapper; mechanism for feeding and disposing a wrapper web in the path of an article for engagement therewith as an article is placed on said table, including a plurality of spaced conveyors mounted between said surfaces, transverse web engaging rods fixed to said conveyors, and means operative after said wrapper has been clamped by said first-named means for moving said conveyors to cause one of said rods to travel between said guide and clamping means to engage and feed more web to form the next wrapper. 45

15. Wrapping mechanism comprising a pair of spaced endless conveyors, wrapper engaging loop forming rollers connected at their ends to said conveyors, and spaced equidistantly therealong, and means for moving said conveyors to cause said rollers seriatim to engage and feed a loop of wrapper web into the path of an article to be wrapped. 60

16. Wrapping mechanism comprising a pair of laterally spaced endless conveyors mounted in substantially parallel vertical planes, transverse rods connected at their ends to said chains, and spaced equidistantly along said chains, means for moving said conveyors to bring one of said rods 70

into engagement with a continuous web of wrapping material for feeding a loop length of said web and means for cutting one end of said loop length of web and disposing the end thereof in the path of an article to be wrapped. 5

17. In a wrapping machine provided with web feeding mechanism, an article guideway, means for supporting a wrapper draped across an end of said guideway, and means for projecting articles in succession from said guideway and into said wrapper to partially enwrap an article with said web extending uncut therefrom; wrapper feeding mechanism comprising endless conveyors, a plurality of rollers mounted on said conveyors equidistantly spaced along said conveyors and feeding transversely therebetween, and means operative after the complete encirclement of a wrapper about each article for driving said conveyors to cause said rollers to engage said uncut extended portion of said web of wrapper material seriatim and drape the free end thereof in the path of the next article to be wrapped. 10

18. In a wrapping machine provided with web feeding and cutting mechanism, an article guideway, means for supporting a wrapper draped across the end of said guideway, and means for projecting an article to be wrapped into said wrapper and partially wrapping the same therein, a traveling wrapper draping mechanism, comprising endless conveyors positioned adjacent opposite sides of said guideway, a plurality of wrapper engaging rollers mounted on said conveyors and extending therebetween equidistantly along said conveyors, means for driving said conveyors to cause one roller after the other to engage said wrapper web and disposed the same in the path of the next article to be wrapped, and means for adjusting the position of said rollers relative to their point of engagement with said web for controlling the overlap of said wrapper on said article. 25

19. In a wrapping machine provided with web feeding and cutting mechanism, an article guideway, means for supporting a wrapper draped across the end of said guideway, and means for projecting an article to be wrapped into said wrapper and partially wrapping the same therein, a second wrapper supporting means for holding said web extended relative to said first named supporting means, endless conveyors positioned adjacent opposite sides of said guideway, a plurality of wrapper engaging rods mounted on said conveyors and extending outwardly therefrom, said rods being positioned equidistantly along said conveyors, means for intermittently moving said conveyors to cause said rods to travel between said first-named and second-named wrapper support means to engage said wrapper web seriatim and drape the same in the path of the next article to be wrapped, and means for cutting said wrapper at the conclusion of each movement of said conveyors. 35

20. In a wrapping machine, a mechanism for wrapping an article in the free end of a web of wrapping material including, a traveling web engaging member movable across the path of one article while another article is partially wrapped within the free end of said web, means to complete the circumferential enwrapping of said last-named article in said free end, means for driving said member in a closed and continuous path during its coaction with said wrapper web, and means for controlling the amount of travel of said member after said member engages said web. 40

21. In a wrapping machine having web feeding and cutting mechanism, means for moving a succession of articles into said machine, and a guideway over which said articles are moved, mechanism for positioning a wrapper web in the path of each article moving from said guideway, means for completing the encirclement of each wrapper about each of said articles, with said web extending uncut upon said partially wrapped article, a traveling web feeding member operative after a wrapper has been encircled about an article, and means for driving said member in a single direction and in a closed path into and out of engagement with said uncut web extending beyond said partially wrapped article for draping the free end of said web in the path of the next article to be wrapped, and means for cutting said web when the movement of said member ceases.

22. Wrapping mechanism comprising a pair of spaced driven conveyors, wrapper engaging rods connected at their ends to said conveyors spaced equidistantly therealong, conveyor supporting and driving members, shafts mounting said members, means for moving said conveyors to cause said rods seriatim to engage and feed a length of wrapper, said means including a driven gear provided with a sleeve mounted on one of said shafts, a driving gear engaging said driven gear, and a releasable clamp secured to said shaft and connecting said sleeve and shaft for common motion, and means for loosening said clamp to disconnect said sleeve from said shaft whereby said conveyors can be moved independently of said driven gear to vary the position of said rods relative to said driven gear.

23. Wrapping mechanism comprising a pair of spaced endless traveling supporting members, wrapper engaging rods connected at their ends to said members and spaced equidistantly therealong, means for moving said members to cause said rods seriatim to engage and feed a wrapper web into the path of an article to be wrapped including, rack and pinion driving means, driving and driven gears associated with said rack and pinion, and means for incapacitating said driving and driven gears when a roller has fed a wrapper web into the path of an article.

24. Wrapping mechanism comprising a pair of spaced endless travelling supporting members, wrapper engaging rods connected at their ends to said members and spaced equidistantly therealong, means for moving said members to cause said rods seriatim to engage and feed a wrapper web into the path of an article to be wrapped including, rack and pinion driving means, driving and driven gears associated with said rack and pinion, means for incapacitating said driving and driven gears when a roller has fed a wrapper web into the path of an article, and means for adjusting the position of said rollers relative to said web to advance or retard the engagement of a roller with said web.

25. Wrapping mechanism comprising a pair of spaced traveling conveyors, wrapper engaging loop pulling rollers connected at their ends to said conveyors spaced equidistantly therealong, conveyor supporting and driving shafts mounting said members, and means for moving said conveyors to cause each of said rollers seriatim to engage and feed a loop length of wrapper web.

26. Wrapping mechanism comprising a pair of spaced driven conveyors, wrapper engaging rods

connected at their ends to said conveyors and spaced equidistantly therealong and constructed and arranged to feed wrapping material into the path of articles to be wrapped, and mechanism for moving said conveyors to cause said rollers seriatim to engage and feed a wrapper web, said mechanism comprising a driven member for said conveyors, a driving member coacting with said driven member, a clutch associated with said driving member, means for intermittently moving said driving member, and a device coacting with said clutch for disconnecting the driving relation between said driving and driven members to stop the movement of said conveyors and rods after each rod has disposed a predetermined quantity of wrapping material in the path of an article to be wrapped.

27. In a wrapping machine having vertically spaced article supporting and guiding surfaces, a lifter table for conveying an article partially enveloped in a wrapper from one surface to another, and means for moving said partially wrapped article from said lifter table to complete the wrapping thereof, mechanism for feeding and disposing the free end of a continuous web of wrapping material in the path of an article moving over said supporting surface including a plurality of spaced conveyors extending between said surfaces, web engaging devices fixed to said conveyors, means operative after said table has conveyed an article to a point adjacent said guiding surface for moving said conveyors to cause one of said devices to engage and feed additional web for the next wrapper, clutch means for stopping the movement of said conveyors when said length of web has been fed, and means for severing said web to form said wrapper.

28. In a wrapping machine, a pair of spaced conveyors, wrapper engaging rods connected to said conveyors and constructed and arranged to engage a web of wrapping material, mechanism for moving said conveyors to cause said rollers seriatim to feed a length of said web into position to receive an article to be wrapped, said mechanism comprising a driven member arranged to move said conveyors, a driving member for driving said driven member, a clutch associated with said driving member, a throwout pawl mounted on said driven member, a toothed element on said driving member adapted to be engaged by said pawl, means for driving said driving member, a throwout rod constructed and arranged to engage said pawl, and means operative when one of said rods has effected the feed of a predetermined quantity of web for moving said rod into engagement with said pawl to disengage said driving relationship between said driving and driven members and stop the movement of said rods.

29. Wrapping mechanism comprising a pair of spaced endless conveyors, wrapper engaging loop forming rollers connected at their ends to said conveyors, and spaced equidistantly therealong, means for moving said conveyors to cause said rollers seriatim to engage and feed a loop of wrapper web into the path of an article to be wrapped, and means for adjusting the position of said rollers relative to the point of engagement thereof with said wrapper web to control the length of loop fed by each of said rollers.

LEON V. WHIPPLE.
JAMES D. WELLS.

CERTIFICATE OF CORRECTION.

Patent No. 2,374,148.

April 17, 1945.

LEON V. WHIPPLE, ET AL.

It is hereby certified that error appears in the printed specification of the above numbered patent requiring correction as follows: Page 5, first column, line 19, claim 4, strike out "unidirectional" and insert the same in line 17, same page and column, before the word "path"; page 6, second column, line 50, claim 19, before "endless" insert --a traveling wrapper draping mechanism--; page 7, second column, line 26, claim 27, for "path of" read --path of--; and that the said Letters Patent should be read with this correction therein that the same may conform to the record of the case in the Patent Office.

Signed and sealed this 31st day of July, A. D. 1945.

Leslie Frazer
